B. R. STARE, F. H. WELLING & W. CONOVER.
ACCOUNTING AND ACCOUNT ADJUSTING DEVICE.
APPLICATION FILED JULY 15, 1915.

1,286,137.

Patented Nov. 26, 1918.

3 SHEETS—SHEET 1.

Witnesses:

W. S. Gaylord.

Chas. H. Buell.

Inventors:
Burton R. Stora,
Francis Harvey Wetting
and Wilbur Conover,
By Dyerforth Lee, Button and Webster,
Attleboro.

B. R. STARE, F. H. WELLING & W. CONOVER,
ACCOUNTING AND ACCOUNT ADJUSTING DEVICE.
APPLICATION FILED JULY 15, 1915.

1,286,137.

Patented Nov. 26, 1918.

UNITED STATES PATENT OFFICE.

BURTON R. STARE, OF SEATTLE, WASHINGTON, FRANCIS HARVEY WELLING, OF SAN FRANCISCO, CALIFORNIA, AND WILBUR CONOVER, OF CLEVELAND, OHIO, ASSIGNORS TO NATIONAL HOTEL SCRIP COMPANY, OF CHICAGO, ILLINOIS, A CORPORATION OF ILLINOIS.

ACCOUNTING AND ACCOUNT-ADJUSTING DEVICE.

1,286,137.

Specification of Letters Patent. Patented Nov. 26, 1918.

Application filed July 15, 1915. Serial No. 39,969.

To all whom it may concern:

Be it known that we, BURTON R. STARE, FRANCIS HARVEY WELLING, and WILBUR CONOVER, citizens of the United States, residing at Seattle, Washington, San Francisco, California, and Cleveland, Ohio, respectively, have invented a new and useful Improvement in Accounting and Account-Adjusting Devices, of which the following is

10 a specification.

This invention relates particularly to devices for use by traveling-men, whereby hotel expenses may be met and accountings of hotel expenses rendered in such manner 15 as to render it unnecessary for the traveling-man to carry on his person any large sums of money and to insure regular and proper accountings to the employer.

The primary object of the invention is to 20 provide simple and effective means for enabling the above-indicated result to be obtained.

The invention contemplates the issuance of 25 scrip-books by a company (X Hotel Scrip Company, for illustration), which has, or will enter into, contract relations with hotels throughout the country, providing for the acceptance of such scrip by the hotels in lieu of currency and subject to a certain 30 discount. Such scrip books are purchased by the employer and furnished by the employer to his traveling-salesmen, by whom the scrip is used, in lieu of currency, in payment of hotel expenses. Suitable provision 35 is made to insure against fraudulent use of the scrip, and the scrip, as used, is indorsed on the back with the hotel statements, showing the itemized expense accounts.

The invention contemplates an arrangement 40 by the scrip-issuing company with one or more principal banks or depositaries, whereby scrip will be redeemed when presented at said depositaries. For illustration, the United States may be divided into western, central and eastern zone, and arrangements may be made for a depositary in each one of said zones. Provision is made whereby the scrip received by any hotel may be, by that hotel, deposited in a local bank; 45 and the scrip may pass through the clearing house and eventually reach one of the depositaries, whence it is returned to the scrip-issuing company and finally returned to the

employer, who thus is able to receive the itemized hotel expense accounts of his several employees. The invention provides means for enabling a system of this character to be put into practical operation. Such means are illustrated in the accompanying drawings, in which—

Figure 1 represents, in open condition, a scrip-book; Fig. 2, a portion of the scrip taken from the scrip-book and having applied thereto a hotel statement, showing itemized expenses; Fig. 3, a broken plan view of the scrip-book cover; Fig. 4, an office file envelop for use in the office of the scrip-issuing company; Fig. 5, a reverse-side view of the same envelop; Fig. 6, a sectional view illustrating the manner in which the scrip is folded in the scrip-book; Fig. 7, an end view of the scrip-book in folded condition; Fig. 8, a face view of a hotel deposit envelop for use by the hotel accepting the scrip, the envelop being shown brokenly to expose a carbon slip and a hotel record slip contained in the envelop; and Fig. 9, a view of the hotel record slip removed from the envelop shown in Fig. 8.

In the preferred embodiment illustrated, 80 the invention comprises a scrip-book A; a hotel statement B; an office file envelop C; and a hotel deposit envelop D adapted to receive therein a hotel record slip D' and a carbon slip D².

The scrip-book A preferably comprises a cover 1 and folded scrip 2 contained therein. The cover 1 preferably comprises a back portion 1^a and flaps 1^b and 1^c. The cover may be made of thin linen cardboard, 85 having lines of folding 1^d.

The scrip 2 may comprise a long strip of paper folded in the manner of a mileage ticket and having its bottom or final end pasted in the back portion of the cover, as 95 indicated at 3 in Fig. 6. The scrip comprises an office record coupon 2^a at the free or upper end of the scrip, and the scrip-proper 2^b, which is provided with a series of value indicating figures 4, starting with five cents and ranging as high in value as may be desired. For illustration, it is convenient to use a scrip having value indicating characters which run to the amount of \$100.00.

The office record coupon 2^a is provided 105 with a serial number blank 5 (shown as con-

taining the serial number 36345), the scrip proper 2^b with similar serial number blanks 5^a, receiving the same serial number; and the section 1^c of the cover is provided with 5 a serial number blank 5^b which receives the same serial number. The character W is used to indicate the western zone, for instance.

The office record coupon 2^a is provided 10 with a blank 6 for the name of the employee who is the holder of the scrip; with a blank 3^a for the name of the employer; and with a blank 6^b for the signature of the employee. Thus, in the illustration given, the scrip is 15 shown as issued to John Doe, whose firm is Doe & Company, of Chicago, Illinois; and the coupon is signed by John Doe at the blank 6^b.

On the inner surface of the flap 1^b of the 20 cover is printed a contract 7, which sets forth particularly the conditions under which the scrip is to be used; and at the bottom is provided a signature blank 8 for the signature of the employee or original 25 holder of the scrip-book. On the inner surface of the other flap 1^c is printed the name of the scrip-issuing company (here shown as X Hotel Scrip Co.), and a signature blank 9 is provided for the signature of the holder. 30 A signature blank 10 is also provided for the name of the employer purchasing the scrip-book. Upon the inner surface of the cover-section 1^c are also printed the words "Good in payment for the following items"; 35 and at the point 11, the items for which the scrip is to be accepted by the hotel. While the scrip illustrated in Fig. 6 is short, it will be understood that the scrip may be of any desired length.

40 The hotel statement B may be in the form of a blank bearing the name of the hotel (in the illustration given, the Z Hotel, Stockton, Cal.); a date blank, indicated at 12; and an item list, indicated at 13. A blank 13^a is 45 also provided for the signature of the holder of the scrip. In the illustration given, the hotel statement is shown printed on a sticker, which may be applied to the rear side of the portion of the scrip used in payment of the hotel bill. If desired, however, the hotel may be provided with a stamp bearing thereon the printed form, which may be stamped upon the back of the scrip 50 2^b, the charges for the several items being 55 filled in with ink.

Fig. 3 shows brokenly the cover 1, the lower portion of the inner surface of the back of which is provided with a personal description table 14, upon which may be 60 noted the personal characteristics of the holder of the scrip-book.

The office file envelop C bears the name of the scrip-issuing company, and is provided with a serial number blank 15, which receives the same serial number as the scrip-

book with which it corresponds, namely, the number 36435. The envelop also bears the inscription "\$100.00 scrip file", indicating the total face value of the corresponding scrip-book. The envelop also is provided 70 with a blank 16, for the signature of the original holder, and with a blank 17, for the name of his firm or employer. The front side of the envelop is further provided with columns 18, 19, and 20, at the upper ends of 75 which are respectively, the words "Hotel, Number, Amount". At the bottom of the column 20 is a blank 21 for the total; and there is also provided a blank 22 for the date when the transaction is completed by 80 the return of the last portion of the scrip. As shown in Fig. 5, the reverse surface of the envelop C may be provided with a gummed portion 23, upon which the office record coupon 2^a of the scrip-book may be 85 pasted.

The hotel deposit envelop D bears the inscription "Hotel deposit envelop", also the inscription "Accepted X Hotel scrip herein"; also a blank 24 for the name of the bank 90 through which the scrip is cleared. The envelop further bears the inscription "Payable at X Trust Company, San Francisco", and is provided with a scrip number column 25, and with an amount column 26. The columns bear at their top, respectively, the words "Scrip book number" and "Amount of face value". At the bottom of the columns is a blank 27 set opposite the words "Total face value"; and below this is a blank 100 28, set opposite the words "Total net value". The envelop also bears the inscription, for illustration, "Net value is 90 per cent. of face value".

The hotel record slip D' corresponds approximately in size with the envelop within which it fits. The card is provided with a date blank 29, in which may be indicated the date of deposit; and the card is further provided with columns 25^a and 26^a, and 110 blanks 27^a and 28^a, which correspond with the columns 25 and 26 and the blanks 27 and 28. The carbon slip D² acts as a transfer slip, so that when the figures are written upon the envelop P, a duplicate record will be made 115 on the hotel record slip D'.

The manner in which the improved means are used may be described briefly. The scrip-issuing company (X Hotel Scrip Company) sells to an employer, say Doe & Company, scrip-books for the traveling salesmen of Doe & Company. This may be done at a discount of, let us say, three per cent. of the face value of the scrip-book. In the meantime, the scrip-issuing company has arranged with the hotels throughout the country to receive the scrip in lieu of cash in payment of hotel bills, the hotels agreeing to allow a discount of, let us say, ten per cent. from the face value of the scrip, to the scrip- 120 125 129

issuing company. When the transaction with the employer (Doe & Co.,) is completed, the office record coupon ^{2a} is detached from the scrip-proper and is retained by the scrip-issuing company, being preferably pasted on the reverse side of the office file envelop C. The holder of the scrip presents the scrip-book to a hotel in payment of his bill; the hotel cashier removes the requisite amount of scrip to cover the bill; the hotel statement is applied or stamped upon the back of the removed portion of the scrip, and serves as a hotel indorsement; and as the hotel receives the scrip from various holders of scrip-books, the hotel places the scrip in the hotel deposit envelop, noting on the envelop the number of the scrip-book and the value of the accepted scrip. A record of this data is transferred to the hotel record slip D'. When the hotel desires to make a deposit it indorses the hotel deposit envelop, notes upon the envelop the total face value of the scrip contained in the envelop, and the total net value, these items being transferred to the card or slip D'. In making out its regular bank deposit slip, the hotel lists, along with checks, currency, etc., hotel scrip to the amount of the net value to the hotel of the scrip within the envelop. The scrip is then cleared in the same manner as checks, eventually finds its way to one of the main depositaries of the X Hotel Scrip Company, and finally is delivered to said company. When the scrip from a given book has all been delivered to X Hotel Scrip Company, said company returns the scrip to the purchaser (Doe & Co.,) and retains the office file envelop C, upon which has been noted, in due course, the record of the portions of scrip returned to the scrip-issuing company, the numbers corresponding with the hotels which accepted the scrip, etc. As will be surmised from the foregoing, the scrip-issuing company assigns a number to each hotel with which the scrip-issuing company has a contract providing for the acceptance of its scrip.

The means provided for carrying this system into effect enables the purchaser of the scrip (the employer) to secure a discount. The scrip-issuing company is able to allow its discount and to meet its own operating expenses and obtain a satisfactory profit from the larger discount allowed by the hotels; and the hotel gains an advantage by the assured high class patronage which it receives by virtue of the arrangement. The employer (Doe & Company) also is assured of itemized accountings which are made at the time the hotel bills are settled, so that the employer is assured of more accurate accountings than can ordinarily be expected, and the chance for fraud is largely eliminated. Moreover, the danger of losing or dissipating funds, where large amounts

are carried on the person, is obviated by this means.

The foregoing detailed description has been given for clearness of understanding only and no unnecessary limitation should be understood therefrom but the appended claims should be construed as broadly as permissible in view of the prior art.

What we regard as new and desire to secure by Letters Patent is:

1. Accounting and account adjusting means, comprising a scrip-book having a signature blank for the holder of the book and provided with a serial number, scrip having a corresponding serial number and provided with a column of value indicating figures; and a hotel statement applied to the scrip and bearing an itemized expense account blank.

2. Accounting and account adjusting means, comprising a scrip-book bearing a serial number and provided with a signature blank for the signature of the holder, scrip contained therein provided with a corresponding serial number, and having as a part thereof an office record coupon bearing the same serial number and having a signature blank for the holder of the scrip-book, and an office file envelop bearing the same serial number and having a signature blank for the signature of the holder of the scrip-book.

3. Accounting and account adjusting means comprising a scrip-book bearing a serial number and provided with a signature blank for the signature of the holder, scrip contained therein provided with a corresponding serial number, and having as a part thereof an office record coupon bearing the same serial number and having a signature blank for the holder of the scrip-book, a hotel statement blank associated with the scrip, and an office file envelop bearing the same serial number and having a signature blank for the signature of the holder of the scrip-book.

4. Accounting and account adjusting means, comprising a scrip-book bearing a serial number and provided with a signature blank for the signature of the holder, scrip contained therein provided with a corresponding serial number, and having as a part thereof an office record coupon bearing the same serial number and having a signature blank for the holder of the scrip-book, and an office file envelop for the use of the scrip-issuing company bearing a signature blank for the signature of the holder of the scrip-book and provided with columns for listing the hotels accepting the corresponding scrip, and the values of the scrip portions accepted by such hotels.

5. Accounting and account adjusting means comprising a book bearing a serial number and the signature of the holder,

- scrip bearing the name of the scrip-issuing company, and the signature of the scrip-book holder, and bearing also the same serial number, and a hotel deposit envelop provided with a column adapted to receive scrip-book numbers and provided with an associated column adapted to have listed therein the values of scrip-portions taken from various scrip-books, blanks being provided at the bottom of said columns for listing the total face value of the scrip and the total net value of the scrip.
6. Accounting and account adjusting means comprising a book bearing a serial number and the signature of the holder, scrip bearing the name of the scrip-issuing company, and the signature of the scrip-book holder, and bearing also the same serial number, a hotel deposit envelop provided with a column adapted to receive scrip-book numbers and provided with an associated column adapted to have listed therein the values of scrip-portions taken from various scrip-books, blanks being provided at the bottom of said columns for listing the total face value of the scrip and the total net value of the scrip, a hotel record slip received in said envelop and provided with corresponding columns and blanks, and a transfer slip received in said envelop.
7. Accounting and account adjusting means, comprising a scrip-book having a cover and scrip contained therein and provided with a common serial number, a hotel deposit envelop provided with a scrip-book number column, and an associated column for recording the values of the scrip portions, and an office file envelop for the scrip-issuing company provided with a column for hotel numbers, a date column, and an amount column.
8. Accounting and account adjusting means, comprising a scrip-book having a cover and scrip contained therein and provided with a common serial number, a hotel deposit envelop provided with a scrip-book number column, a hotel record slip provided with corresponding columns and received in said envelop, and an associated column for recording the values of the scrip portions, and an office file envelop for the scrip-issuing company provided with a column for hotel numbers, a date column, and an amount column.
9. Accounting and account adjusting means, comprising a scrip-book having a cover provided with a serial number and a signature blank for the holder of the book, and having scrip provided with the same serial number and provided with an office record coupon bearing the same serial number, a hotel statement blank associated with said scrip, a hotel deposit envelop provided with a scrip-book number column and with a column for noting the values of the scrip portions, and an office file envelop for the scrip-issuing company bearing the same serial number and provided with a hotel number column, a date column and an amount column.
10. In means of the character set forth, a flexible cover bearing a serial number and provided with means for identifying the scrip-book holder, and scrip bearing the same serial number and provided with an office record coupon having a signature blank for the signature of the holder of the scrip-book.
11. In means of the character set forth, a scrip-book cover bearing a contract setting forth terms of use of the scrip and provided with a signature blank for the signature of the holder of the book, said cover bearing also a list of items for which scrip will be accepted in payment, and a serial number, and scrip in said book bearing the name of the scrip-issuing company and provided with a signature blank for the signature of the holder of the book, said scrip bearing the same serial number as the cover.
12. In means of the character set forth, the combination of an office file envelop bearing a serial number and a signature blank for the name of the original holder, said envelop having thereon a hotel number column, a date column, and an amount column; and an office record coupon associated therewith, said office record coupon bearing the same serial number and a signature blank for the signature of the original holder.
13. In means of the character set forth, the combination of a hotel deposit envelop bearing a blank for the name of a bank where deposit is made and bearing a blank for the name of the hotel which is to receive credit, said envelop bearing a scrip-book number column and an amount column for the face value of the charges of the hotel, and bearing also total face value and total net value blanks, and a hotel record slip associated therewith having scrip-book number column and amount column corresponding with those on said deposit envelop and having also total face value and total net value blanks corresponding with those on said envelop.
